H. I. STEFFA

HEAT EXCHANGE APPARATUS

Filed Aug. 8, 1921

Inventor
Homer J. Steffa
By J. C. M. Swanson
Attest

UNITED STATES PATENT OFFICE.

HOMER I. STEFFA, OF CHICAGO, ILLINOIS.

HEAT-EXCHANGE APPARATUS.

Application filed August 8, 1921. Serial No. 490,813.

To all whom it may concern:

Be it known that I, HOMER I. STEFFA, a citizen of the United States, residing at 425 N. Central Ave., Chicago, in the county of Cook and State of Illinois, have invented 5 certain new and useful Improvements in Heat-Exchange Apparatus; and I do hereby declare the following to be a full, clear, and exact description of the invention, such as 10 will enable others skilled in the art to which it appertains to make and use the same, reference being had to the accompanying drawings, and to the letters of reference marked thereon forming part of this specification.

15 This invention relates to heat exchange apparatus and the object thereof is to provide means whereby the fluid to be heated or cooled is caused to flow both longitudinally and transversely through a chamber, through which tubes extend, which tubes conduct the heating or cooling fluid through said chamber, so that the fluid to be heated or cooled will absorb heat from, or give up heat to the tubes.

20 25 The features of my invention are herein-after fully set forth and described, and are illustrated in the accompanying drawings, in which:—

Figure 1, is a side view of my improved apparatus with a portion of the shell thereof broken away, showing the internal arrangement thereof in longitudinal section.

Figure 2, is an end view of the same on the line 2—2 in Fig. 1, with the end plate thereof removed.

Figure 3, is a transverse section of the same on the line 3—3 in Fig. 1.

Figure 4, is a plan view of one of the transverse partition walls shown in section 40 in Fig. 1.

Figure 5, is an edgewise view of a pair of said plates looking in the direction of the arrow in Fig. 4.

Figure 6, is an enlarged detail showing 45 the means of securing tubes in my improved apparatus.

In these drawings A indicates a cylindrical shell having flanges A' on the ends thereof, and tubular inlet and outlet 50 branches A² and A³ adjacent to the ends thereof.

Within the shell A is arranged a series of transverse plates B (see Fig. 4) which

are provided on both sides with ribs B' the edges of which meet each other as shown 55 in Figs. 1 and 5. Each one of the plates B has a portion of its periphery cut out as shown in Fig. 4, which leaves a notch B², through which fluid can flow from one side of said plate to the other. 60

When placed in position in the shell A, as shown in Fig. 1, the notch B² of each alternate plate B is at the bottom, as shown in Fig. 4, and at the top of each intermediate plate, as indicated in Fig. 5. It will 65 be seen that fluid entering the tubular opening A² will pass through the notch B² of the first plate B, and then pass successively around the ends of the ribs B', and then pass through the notch B² of the next plate, 70 and so on until it has traveled transversely and longitudinally the entire length of the shell A, and is discharged through the opposite tubular opening A³.

The plates B are each provided with 75 circular holes through which longitudinal tubes C are passed, the ends of said tubes C being secured in plates D which fit against the flanges A' of the shell A. These tubes are secured in the plates D in any suitable 80 manner; but it is preferable to use the type of fastening used in Fig. 6, which consists in counter-boring and tapping the tube opening in the plate D, and then placing a suitable packing d therein and providing 85 an externally threaded gland d', which is adapted to be secured into said counter-bored opening around the end of the tube C so as to compress the packing d therein. This provides a very efficient fastening, 90 which, while maintaining a tight joint between the plate D and tube C, allows of a sufficient relative movement of the tube C and plate D to compensate for differences 95 in expansion.

Against the plates D at each end of the shell A, I place hollow headers E which are provided with circular openings on each face thereof so that access may be had to the ends of the tubes through said headers E, as illustrated in Fig. 2. These headers E are also provided with inlet and outlet openings E² and E³. The outer face of the headers is covered with a plate E³, so that fluid entering the inlet E² at the left hand end 100 of the apparatus will flow through the 105

tubes C into the header at the right hand, and out through the opening E'.

- In operation, fluid to be treated is introduced into the shell A through the inlet opening A², and therefrom it enters successively the spaces between the transverse plates B and flows transversely around the ends of the flanges B' of said plates B until it is discharged through the tubular opening A³. The heating or cooling fluid enters the inlet branch E² at the left hand, and flows through the tubes C into the header E at the right hand and out through the opening E' so that the heating fluid in the pipes will contain more heat at the left hand end, where the contents of the shell A is the hottest, than at the right hand of the apparatus where the material to be heated has just entered.
- It will be obvious from the foregoing description of the construction and operation of this apparatus, that it can be used with equal facility in either heating or cooling the contents of the shell A.
- Having thus fully shown and described my invention so that others can utilize the

same, what I claim as new and desire to secure by Letters Patent is:

1. In an apparatus of the class described, a casing having inlet and outlet openings at opposite ends thereof, a series of transverse walls therein, each wall having an opening through which fluid may flow, the said openings being located alternately in the top and bottom of the walls, staggered horizontal partitions between said transverse walls, a series of longitudinal tubes passing through said casing and through said transverse walls, and secured in plates on the ends of said casing, and header chambers on the ends of said casing covering the ends of said tubes.
2. In an apparatus of the class described, a casing having inlet and outlet openings adjacent to the ends thereof, a series of tubes passing longitudinally through said casing and secured in the end walls thereof, a series of transverse walls in said casing through which said tubes pass, and staggered horizontal walls between said transverse walls.

In testimony whereof I affix my signature.
HOMER I. STEFFA.
